UNITED STATES PATENT OFFICE.

ISIDOR GREENWALD, OF NEW YORK, N. Y., ASSIGNOR TO ASTORLOID MANUFACTURING CO. INC., OF BROOKLYN, NEW YORK, A CORPORATION OF NEW YORK.

COIL MOUNTING FOR RADIO APPARATUS.

Application filed August 10, 1922. Serial No. 580,913.

To all whom it may concern:

Be it known that I, ISIDOR GREENWALD, a citizen of the United States, and a resident of New York, in the county of New York and State of New York, have invented certain new and useful Improvements in a Coil Mounting for Radio Apparatus, of which the following is a full, clear, and exact specification.

10 This invention relates to a class of devices adapted to be used in conjunction with wireless telegraph systems.

My invention has for its object primarily to provide a mounting designed to be employed for removably interposing three co-operative receiving coils in a wireless electric system whereby the wave currents received may be regulated to vary the clearness of the sounds transmitted, and which 20 is of a manually operative type tending to obviate liability of the body of the attendant of the apparatus to interfere with the electric field surrounding the receivers by conductive absorption of the wave currents.

25 The invention consists essentially of an insulated base having three spaced pairs of aligned electric conductors, each including an insulated socket and a spaced insulated post so that three co-operating receiving

30 coils adapted for wireless electric systems may be removably mounted on the base in spaced parallel arrangement. When in use the base is supported so that the wiring of the aerial of the wireless system leads separately to each socket and each post of each conductor.

35 The central pair of conductors are stationary on the base, while the other conductors are adapted to be rotatably swung toward and from the stationary conductors

40 for varying the space between the receiving coils so that the clearness of the sounds received may be regulated, and means is provided whereby the rotatable conductors may be manually adjusted at a distance for serving to prevent the body of the operator from conductively interfering with the electric field surrounding the receiving coils.

45 A further object of the invention is to provide a coil mounting of a simple, efficient and durable construction which may be made in any suitable form and size.

With these and other objects in view,

the invention will be hereinafter more fully explained with reference to the accompanying drawing forming a part of this specification in which similar characters of reference indicate corresponding parts in all the views, and will then be pointed out in the claims at the end of the description.

55 In the drawing, Figure 1 is a side elevation of one form of coil mounting embodying my invention.

Fig. 2 is a top plan of the device.

Fig. 3 is a sectional view, partly in detail, taken on the line 3—3 of Fig. 2 and 60 which shows in dotted lines part of a form of receiving coil for being supported by the mounting, and

Fig. 4 is a sectional view, partly in detail, taken on the line 4—4 of Fig. 2. 70

The device or mounting has a base 10 which may be of vulcanized rubber, fibre or other suitable insulating material, and this base has a bottom plate 11 of preferably a substantially rectangular shape, on the 75 upper face of which at its side edges are two walls 12, 13 disposed in spaced parallel arrangement. The walls 12, 13 may be of suitable heights, and may be of lengths similar to the length of the bottom plate. 80

Between the insulated side walls 12, 13 of the base 10 are spaced pairs of aligned electric conductors, as 14, 15, 16, each pair including a metallic post 17 and a metallic socket 18 which is in aligned spaced relation 85 to the post. The post and socket of each pair of the conductors are separately insulated by being embedded in a block of vulcanized rubber or other insulating material.

Thus there are three of the insulated blocks, as 19, 20, 21, which are preferably of substantially rectangular shapes, and all of the blocks are disposed edgewise in spaced parallel relation across the space between the side walls 12, 13 of the base 10. All 90

of the insulated blocks may be arranged so that their upper edges are on similar planes to the upper edges of the side walls of the base, and the blocks are of sizes so that their lower edges are spaced from the bottom plate of the base. The posts 17 of the conductors are of lengths so that their upper ends protrude some distance above the upper edges of the insulated blocks 19, 20, 21, 100

and the upper open ends of the sockets of the conductors terminate flush with the upper edges of the blocks so that receiving coils, as A, B, C, of well-known forms adapted for wireless electric systems, each having on its lower end a protruding conductive post, as D, and having a spaced conductive socket, as C, may be removably mounted on the blocks and conductively interposed in the wireless system by the posts D of the coils being seated in the sockets 18 of the conductors 14, 15, 16 and by the posts 17 of the conductors being disposed in the sockets C of the coils. The post 17 and socket 18 of the central conductor 15 are held stationary on the base 10 for likewise holding in fixed position the receiving coil B by the insulated block 20 being secured to the base by one or two spaced bolts or screws, as 22, 23, being driven through threaded holes in the side wall 12 of the base and in threaded sockets in the block 20 and also by one or two spaced bolts or screws, as 24, 25, engaging holes in the side wall 13 of the base and in threaded sockets in this block. The screws 22 and 24 are of lengths so that they conductively engage the post and the socket of the conductor 15, while the screws 23 and 25 may be separated from the post and socket. The posts and sockets of the conductors 14 and 16 are adapted to be rotatably swung toward and from the stationary conductors 15 for permitting the receiving coils A and C to be adjustably spaced from the receiving coil B, and this is accomplished by providing a manually operative mechanism, as 26. The mechanism 26 has two studs 27, 27^a having one of their ends journaled in holes in the side wall 13 of the base 10, and the other end portions of the studs are embedded in the blocks 19 and 21 as well as having threaded ends which are screwed, as at 28, in threaded holes provided in the lower ends of the sockets 18 of the conductors 14 and 16. In threaded holes provided in the lower ends of the posts 17 of the conductors is screwed, as at 29, the threaded ends of two shafts 30, 31, portions of both of which are embedded in the blocks 19 and 21, and the shafts are also journaled in holes in the side wall 12 of the base 10. The shafts 30, 31 are preferably of lengths so that their outer ends extend beyond the electric field surrounding the receiving coils and the base when the device is in use, and these shafts are also rotatably disposed through fixed sleeves, as 32, 33, which protrude from the side wall 12 of the base. On the outer ends of the shafts 30, 31 are held worm gears 34, 35, and on the outer ends of the sleeves 32, 33 are held corresponding brackets 36, 37. Each of the brackets are substantially U-shaped and both brackets are disposed above the worm gears 34, 35 as well as being arranged on upward diverging inclines so that the free ends of the arms of the brackets are in spanning positions relative to the worm gears. In registered holes in the ends of the arms of the U-shaped brackets are journaled the lower ends of two rods or shafts 38, 39 which are also disposed on upward diverging inclines. On the part of the rods 38, 39 between the arms of the U-shaped brackets are worms 40, 41 which are in mesh with the worm gears 34, 35 of the shafts 30, 31, and on the upper ends of the rods are provided heads or knobs or handles 42, 43 of suitable insulating material. When the rods 38, 39 are rotated by revolving the handles 42, 43 accordingly the rods 38, 39 and worms 40, 41 will be likewise revolved for rotatably swinging the blocks 19, 21 toward and from the block 20 to adjustably space the receiving coils A and C with relation to the receiving coil B for regulating the clearness of the sound waves in the wireless electric system to which the device is applied. The movements of the coils A and C toward the coil B may be limited by stops, as 44, 45, both of which are provided by a single rod which is embedded in the stationary insulating block 20 as well as being of a length so that the ends of the rod extend in opposite lateral directions from the block 20 toward the insulating blocks 19 and 21 which in turn will be limited in their movements to determined distances toward the block 20. When the device is employed in conjunction with a wireless electric system the base 10 is fastened to a suitable support, and to permit the receiving coils A, B, C to be interposed in the system, on the base 10 are provided pairs of binding posts, as 47, 47^a, 48, 48^a, 49, 49^a, all of which are preferably of similar formations and of types so that electric wires, as E, leading from the aerial may be connected to the base. Each of the binding posts has a rod screw, as 50, and one of the end parts of all of the screws are screwed in spaced threaded sockets, as 51, provided in the lower edges of the walls of the base. Two of the sockets 51 terminate at the studs 27, 27^a, while two of the other sockets terminate at the shafts 30, 31, and two of the sockets terminate at the screws or bolts 22, 24 of the stationary block. All of the screws 50 are of lengths as well as being arranged so that their ends within the sockets are spaced from the bottoms of the sockets, while the other end portions of the screws protrude some distances from the underside of the base. In each of the sockets 51 may be a spiral spring 52 of metal, and one of the ends of all of the springs engage the screws 50 of the binding posts to provide conductive connections between the wires E.

and the conductors 14, 15, 16 through the studs 27, 27^a, shafts 30, 31 and screws 22, 24. The springs 52 also provide yielding connections with the studs 27, 27^a and shafts 30, 31 to allow free functioning of the studs and shafts when rotated, as above explained. In practice the coils A, B, C will receive the electric currents over the wires E, through the binding posts 47, 47^a, 48, 48^a, 49, 49^a over the studs 27, 27^a, shafts 30, 31, screws 22, 24, through the posts 17, and sockets 18 of the conductors 14, 15, 16 to and through the terminal posts D and the terminal sockets C of the receiving coils.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:

1. A coil mounting as characterized, comprising an insulated base having a bottom wall with two protruding spaced walls, three spaced insulated blocks between the walls of the base, the central block being stationary and the other blocks adapted to be rotatably swung toward and from the stationary block, three conductive posts, one embedded in and protruding upwardly from each of the blocks, three conductive sockets, one embedded in each of the blocks in spaced relation to its post, a pair of binding posts embedded in and projecting from the base, one being connected to the post of the stationary block and the other connected to the socket of the stationary post, two conductive studs journaled in one of the walls of the base and each of the studs leading to the socket of one of the rotatable blocks, two other binding posts embedded in and extending from the base, each being connected to and yieldingly contacting with each of the studs, two conductive shafts journaled in the other wall of the base and each of the shafts leading to the post of one of the rotatable blocks, both of said shafts extending beyond the base, two more binding posts embedded in and projecting from the base, each connected to and yieldingly contacting with each of the shafts, and means on the shafts, manually operative for rotating each shaft separately for rotatably adjusting the rotatable blocks.

2. A coil mounting as characterized, comprising an insulated base having a bottom wall with two protruding spaced walls, three spaced insulated blocks between the walls of the base, the central block being stationary and the other blocks adapted to be rotatably swung toward and from the stationary block, three conductive posts, one embedded in and protruding upwardly from each of the blocks, three conductive sockets, one embedded in each of the blocks in spaced relation to its post, a pair of binding posts embedded in and projecting from the base, one connected to the post of the stationary block and the other being connected to the socket of the stationary post, two conductive studs journaled in one of the walls of the base and each of the studs leading to the socket of one of the rotatable blocks, two other binding posts embedded in and extending from the base, each connected to and yieldingly contacting with each of the studs, two conductive shafts journaled in the other wall of the base and each of the shafts leading to the post of one of the rotatable blocks, both of said shafts extending beyond the base, two more binding posts embedded in and projecting from the base, each connected to and yieldingly contacting with each of the shafts, a worm gear fixed on the outer end of each of the shafts, two worms, each worm meshing with the worm gear of one of the shafts, and two handles, one on each worm to allow the shafts to be manually revolved for rotating the rotatable blocks toward and from the stationary block.

3. A coil mounting as characterized, comprising an insulated base having a bottom wall with two protruding spaced walls, three spaced insulated blocks between the walls of the base, the central block being stationary and the other blocks adapted to be rotatably swung toward and from the stationary block, three conductive posts, one embedded in and protruding upwardly from each of the blocks, three conductive sockets, one embedded in each of the blocks in spaced relation to its post, a pair of binding posts embedded in and projecting from the base, one connected to the post of the stationary block and the other connected to the socket of the stationary post, two conductive studs journaled in one of the walls of the base and each of the studs leading to the socket of one of the rotatable blocks, two other binding posts embedded in and extending from the base, each connected to and yieldingly contacting with each of the studs, two conductive shafts journaled in the other wall of the base and each of the shafts leading to the post of one of the rotatable blocks, both of said shafts extending beyond the base, two more binding posts embedded in and projecting from the base, each connected to and yieldingly contacting with each of the shafts, two conductive shafts journaled in the other wall of the base and each of the shafts leading to the post of one of the rotatable blocks, both of said shafts extending beyond the base, two more binding posts embedded in and projecting from the base, each connected to and yieldingly contacting with each of the shafts, a worm gear fixed on the outer end of each of the shafts, two worms, each worm meshing with the worm gear of one of the shafts, and two handles, one on each worm to allow the shafts to be manually revolved for rotating the rotatable blocks toward and from the stationary block.

2
on the outer end of each of the shafts, two blocks toward and from the stationary 10
brackets each on the outer end of one of
the shafts, two worms, each rotatably
mounted on one of the brackets and each
8 worm meshing with the worm gear of each
of the shafts, and two handles, one on
each worm to allow the shafts to be man-
ually revolved for rotating the rotatable

block.
This specification signed and witnessed
